Attorney.

UNITED STATES PATENT OFFICE.

EMIL BÖSEBECK, OF BARMEN, GERMANY.

SINGLE-THREAD BONE LACE AND PROCESS OF MAKING THE SAME.

Application filed June 15, 1922. Serial No. 568,623.

To all whom it may concern:

Be it known that I, EMIL BÖSEBECK, a citizen of Germany, residing at Barmen, Germany, have invented certain new and useful Improvements in Single-Thread Bone Laces and Processes of Making the Same, of which the following is a specification.

My invention relates to a machine-made imitation Valenciennes lace and to an improved process of making the same on the so-called single-thread plaiting machine, that is a machine of the type generally described in the U. S. Patent No. 613,380 to

15 Mathére.

The manufacture of machine plaited laces has been perfected in recent years to such an extent that almost all kinds of bobbin or pillow laces may be manufactured by 20 means of the above named single thread plaiting machines, a product being thereby obtained which can hardly be distinguished from the genuine hand-made laces.

One of the few exceptions was the manufacture of the very delicate Valenciennes laces of great delicacy, because the working of threads of the desired fineness upon the plaiting machine presents difficulties on account of the likelihood of frequent breaking 25 of the threads. It became necessary, therefore, in the manufacture of such laces by machinery to employ threads of greater thickness, so that the laces manufactured in this manner were lacking the exceedingly 30 delicate clear ground peculiar to the hand-made goods which latter on account of their fineness of texture were particularly highly valued and were noticeable by their being "hand-made."

According to my invention provision is made to overcome this difficulty by composing the ground of the new machine-made imitation Valenciennes lace of this invention which is to be manufactured on the 35 single thread bone-lace machine from individual braids which instead of the four component threads ordinarily employed consist of only three threads plaited together, and in consequence thereof I am 40 enabled without excessive weakening of the individual threads to produce a ground with plaited meshes of a fineness and clearness heretofore impossible to obtain on machines, and which is peculiar only to the

most delicate hand-made Valenciennes laces. 55 Thus I obtain a lace which, though differing in the number of threads from the real article, has substantially the same appearance as the genuine Valenciennes lace, because the difference of threads in each braid will 60 not be noticed by the naked eye. There is, moreover, the additional advantage that as a result of this novel formation of laces far less bobbins and consequently smaller-sized machines, and less thread material 65 than heretofore are required for the manufacture of such laces by machinery.

In order to make it possible with the lace ground thus produced to also obtain the usual spiders, ribbons and similar patterns, 70 which, in Valenciennes lace, are as a rule worked in a weave-like manner, the threads of the braids of the lace ground are at every place where a pattern is to be formed redistributed into groups of two, four or 75 any other even number of threads which are then utilized in the well known manner for the formation of the patterns.

I have shown my invention as embodied in a piece of lace on the accompanying 80 drawing by way of example.

Figure 1 shows a lace produced in accordance with my invention in its natural size.

Figure 2 is part of the same lace on a 85 greatly enlarged scale.

In the drawing:—*a* indicates the ground formed in the manner of the usual Valenciennes-laces the individual meshes of which are approximately diamond-shaped. The 90 sides of the diamond are formed by single braids which, as shown in Figure 2 of the drawing, are each composed according to my invention of only three braidingly connected threads, *b*, *c*, *d*, plaited together, 95 while in the Valenciennes laces thus far known they consist of four threads each. At certain points spaced from each other the individual braids are connected to each other by the mutual interchange of two 100 pairs of threads, as illustrated at *f* as a result of which the braids are caused to run in zig-zag lines, thus forming longitudinal rows of diamond-shaped meshes. The interconnection of the braids may also be effected by the interchange of only one or of 105 all three pairs of threads, and I do not desire to be limited to the interchange of two

pairs of threads only. It is important, however, that braids or ties which form the substantially diamond-shaped meshes consist each of three, and only three threads plaited together.

For the formation of the usual pattern, thus for instance of a spider *i*, the threads which form the braids are at the respective place redistributed into groups *g*, *g* of only two threads, and they are then interlaced in a substantially weave-like manner for the formation of the pattern. According to the kind of pattern it is desired to obtain I may also assemble four or six threads, as shown for instance with reference to the composition of the ribbon *h*.

The invention is susceptible of a great many different applications and it may be varied and modified to suit the kind of goods to which it is employed and without deviation from the spirit thereof.

I claim:—

1. A machine-made imitation Valenciennes lace comprising a series of braids consisting each of three, and only three threads forming a plait or queue, said braids being arranged in zig-zag lines and connected at their meeting points by a mutual in-

terchange of threads between each two adjacent braids.

2. The method of making an imitation Valenciennes lace on the single-thread plaiting machine comprising the steps of forming a series of braids by plaiting together three, and only three threads each, arranging said braids in zig-zag lines and connecting the same at their meeting points by interchanging a number of threads of one braid with a corresponding number of threads of the adjacent braid.

3. The method of making an imitation Valenciennes lace on the single-thread plaiting machine comprising the steps of producing a ground with substantially diamond-shaped meshes by forming a series of braids by plaiting together three, and only three threads each, and interconnecting said braids at certain intervals, and producing patterns by redistributing the threads which form said braids into groups of an even number of threads and interlacing said threads in a substantially weave-like manner.

In testimony whereof I affix my signature.

EMIL BÖSEBECK.
